ABSTRACT

The invention relates to a device for forming a cover for pots and pans and the like. The device is comprised of a metal frame having a cross member forming a handle. A non-flammable deformable material is placed under the frame and wrapped about the frame to form the cover.

COVER WITH REPLACEABLE COVERING MATERIAL

This is a continuation of application Ser. No. 207,483 filed Dec. 13, 1971, now abandoned.

BACKGROUND OF THE INVENTION

1. Field of the Invention

The invention relates to a device for forming a cover for pots and pans and the like. More specifically, the invention relates to a frame and a disposable, non-flammable, deformable material wrappable about the frame to form a cover for use in cooking.

2.

Prior Art

Covers used in cooking are known; however, all have the disadvantage of having to be cleaned after use. The cleaning process varies in difficulty as the cover varies in material and shape.

Prior art covers having a wire mesh for the covering material is difficult to clean and these do not prevent splattering entirely during such cooking operations as frying.

Another problem with covers for pots and pans is in the insulating of the handle, such that the user does not get burned from the handle. The common solution to this problem is the use of well-known insulating material about the handle or as handle of the cover.

SUMMARY OF THE INVENTION

Therefore, an object of the present invention is to provide a new cover for pots and pans having a disposable material for the covering portion of the cover.

Another objective of the invention is to provide a new cover comprised of a frame and a deformable replaceable heat resistant covering material.

Still another objective of the invention is to provide a new cover comprised of a frame having a cross member for forming a handle that allows use of the cover without the use of heat resistance material as the handle.

Briefly, the invention is comprised of a metal frame. The frame is of desired shape and size to be used with a respective pot or pan. The frame contains a cross member which is used to define a handle and to give strength to the frame structure. A replaceable, deformable, non-flammable material is wrapped about the frame to form the area covering portion of the cover.

It has been found that if an aluminum foil is used as the covering material and the cross member is made of steel and welded to the frame, that the handle formed by the cross member remains cool to touch during the entire cooking operation.

The invention has the advantage of ease of cleaning since only the covering portion of the cover is contaminated and this is removed and disposed of as trash.

Another advantage of the invention is that the frame portion of the cover is light and easily stored.

Another advantage of the invention is that the cover portion once over the frame can be easily perforated to allow for a steaming cooking operation, with no increase in cost.

Another advantage of the invention is the ability of the cross member to remain at a comfortable temperature during cooking operation without the use of costly and often fragile insulating materials.

BRIEF DESCRIPTION OF THE DRAWINGS

The foregoing and other objects, features and advantages of the invention will be apparent from the following more particular description of the preferred embodiment of the invention, as illustrated in the accompanying drawings.

In the drawings:

FIGS. 1 *a*, *b* and *c* constitute an orthogonal drawing showing the preferred embodiment of the frame of the invention.

FIG. 2 is a perspective view of the frame of the preferred embodiment of the invention.

FIG. 3 shows the frame of FIG. 2 atop the covering material of the preferred embodiment of the invention.

FIG. 4 shows the covering material of FIG. 3 wrapped about the frame of FIG. 2 to form the cover of the preferred embodiment of the invention.

DESCRIPTION OF THE PREFERRED EMBODIMENT

FIGS. 1 *a*, *b* and *c* show the top, side and front views respectively of the frame of the invention. It should be realized that the size and shape is not critical, that is, the frame may be circular, square or rectangular. The overall dimensions are dictated by the pot or pan that the cover is to be used with. Generally the outer dimension of the frame is slightly less than the normal dimension of the cover to allow for the covering material.

The outer frame 1 is made of metal such as steel or aluminum. The outer framematerial is in the form of wire, having a circular cross section so as to avoid sharp corners. If it is desired, however, a non-circular cross section may be used, but at an increased probability that damage will be done to the covering material when it is wrapped about the outer frame 1.

A cross member 2 is connected to the outer frame 1 to form the total frame. Cross member 2 is of the same material as the outer frame in the preferred embodiment. The material of the cross member need not be the same material, however, as long as the two materials are capable of being securely connected to each other. The preferred material is steel for both the outer frame 1 and cross member 2. The outer frame 1 is joined to cross member 2 by welding or any other appropriate joining procedure.

Cross member 2 is shaped so as to provide a handle for the total frame when joined to the outer frame as shown in FIG. 2. Generally only one cross member 2 is needed with any given outer frame, however, it may be desired in large covers to have two or more cross members for providing one or more handles and adding strength to this frame structure.

FIG. 3 shows a covering material 3 placed beneath the frame. Covering material 3 is a non-flammable, deformable, replaceable material such as aluminum foil. The covering material is wrapped about the outer frame 1 of the frame to form a smooth bottom of the cover formed by the frame and covering material. The handle portion of cross member 2 is not covered by the covering material 3 as shown in FIG. 4.

It has been found that a cover using aluminum foil as the covering material, and steel for the outer frame and cross member of the frame, that the handle portion of the cross member remains comfortable to the touch and does not rise in temperature to a degree to necessitate the use of pot holders or the like. It has also been

found that the amount of temperature rise is inversely proportional to the cross section of the cross member forming the handle portion of the cover.

When cooking operation is over, the covering material is removed from the frame and disposed of as trash. The frame due to its lightness and open structure allows a number of frames to be easily stacked with the use of minimum space.

It is desired, the covering material may be perforated either before or during the cooking operation to thereby allow the food to steam. Therefore, the cover becomes a multipurpose type easily adaptable to any cooking operation.

While the invention has been particularly shown and described with reference to a preferred embodiment thereof, it will be understood by those skilled in the art that various changes in form and detail may be made therein without departing from the spirit and scope of the invention.

What I claim is:

1. A cover for pots and pans consisting of:
a frame consisting of an outer circular frame having a circular cross-section and a cross member extending along the diameter of said outer circular frame and attached at both ends to said outer circular frame, said cross member being formed into a handle at one location along the length of said cross member, said handle being perpendicular to

said outer circular frame; and
a replaceable, disposable deformable, non-flamable covering material replaceably wrapped about said frame to form the covering of said cover, said covering material maintaining its own shape after being wrapped about said frame so as to maintain itself onto said frame; and
said handle extending above said covering material.

2. A cover for pots and pans consisting of:
a frame consisting of a steel outer circular frame having a circular cross-section and a steel cross member extending along the diameter of said outer frame, said cross members being formed into a handle at one location along the length of said outer frame, said handle being perpendicular to said outer frame;
a replaceable, disposable, deformable, non-flamable covering material of aluminum foil wrapped about said frame to form the covering of said cover so as to support itself upon the frame;
said handle extending above said covering material; and
said aluminum foil and said frame coating so as to maintain said cross member, forming said handle at a moderate temperature when said cover is used during a cooking process.
